Primary Examiner — Marie Fast Horse*(74) Attorney, Agent, or Firm* — Morrison & Foerster LLP**(57) CLAIM**

We claim the ornamental design for a fan, as shown and described.

DESCRIPTION

FIG. 1 is a perspective view of a fan showing our new design; FIG. 2 is a front view thereof; FIG. 3 is a rear view thereof; FIG. 4 is a side view thereof; FIG. 5 is a side view of the opposite side of FIG. 4; FIG. 6 is a top view thereof; and, FIG. 7 is a bottom view thereof.

The broken lines in the drawings depict parts of the fan that form no part of the claimed design.
